CLAIM

The ornamental design for a therapeutic animal collar, as shown and described.

DESCRIPTION

FIG. 1 is a top plan view of a therapeutic animal collar showing my new design;

FIG. 2 is a left side elevational view thereof;

FIG. 3 is a bottom plan view thereof;

FIG. 4 is a right side elevational thereof;

FIG. 5 is an enlarged front elevational view thereof; and,

FIG. 6 is an enlarged rear elevational view thereof.
